CLAIM

The ornamental designs for safety syringe, as shown and described.

DESCRIPTION

FIG. 1 is a front perspective view of a safety syringe;

FIG. 2 is a front view of the safety syringe thereof;

FIG. 3 is a rear view of the safety syringe thereof;

FIG. 4 is a left side view of the safety with the right side being a mirror image thereof;

FIG. 5 is bottom view of the safety syringe thereof; and,

FIG. 6 is a rear perspective view of the safety syringe thereof. The broken lines in the drawings illustrate portions of the safety syringe and form no part of the claimed design.

1 Claim, 4 Drawing Sheets
